(57) **CLAIM**

The ornamental design for an analytical apparatus for drug testing, as shown and described.

DESCRIPTION

FIG. 1 illustrates a side view of an analytical apparatus for drug testing showing an embodiment of my new design; FIG. 2 illustrates a front view thereof;

FIG. 3 illustrates a side view thereof;

FIG. 4 illustrates a back view thereof;

FIG. 5 illustrates a bottom view thereof;

FIG. 6 illustrates a top view thereof; and,

FIG. 7 illustrates a perspective view thereof.

The broken lines depict environmental subject matter, are for illustration only, and form no part of the claimed design.
